SANDBLAST GUN

Andy Jones, Edward J. Kessels, and Ferris A. Ruggles, Denver, Colo., assignors to Engineered Products, Inc., Denver, Colo.

Application October 7, 1949, Serial No. 120,024

4 Claims. (Cl. 51-8)

1

This invention relates to a pneumatic spray gun more particularly of the type designed for abrasive and sand blasting operations, but also adaptable for spraying fluids, if desired.

The principal object of the invention is to provide a pneumatic gun construction in which the parts subjected to wear and abrasion can be quickly and easily removed and replaced without dismantling the entire gun, and in which replaced parts will immediately function efficiently without further adjustment.

Another object of the invention is to so construct the gun that the abrasive container portion of the gun can be quickly and easily removed from the valve and handle portions thereof.

A further object is to provide a highly efficient sealing means for sealing an abrasive or fluid container to the gun.

Other objects and advantages reside in the detail construction of the invention, which is designed for simplicity, economy, and efficiency. These will become more apparent from the following description.

In the following detailed description of the invention, reference is had to the accompanying drawing which forms a part hereof. Like numerals refer to like parts in all views of the drawing and throughout the description.

In the drawing:

Fig. 1 is a side view of the improved spray gun; Fig. 2 is a vertical section therethrough;

Fig. 3 is a detail section, taken on the line 3-3, Fig. 4;

Fig. 4 is a similar section, taken on the line 4-4, Fig. 2;

Fig. 5 is a detail section thru an air valve employed in the improved gun, taken on the line 5-5, Fig. 2; and

Fig. 6 is a horizontal sectional view, looking upward on the line 6-6, Fig. 2.

The improved spray gun comprises a handle casting 10 provided with a hand grip portion 11 of the "pistol" type. A coupling nut 12 is rotatably mounted on the forward extremity of the casing 10 through the medium of a flanged bushing 13. An air feed passage 14 extends into the handle portion 11 to receive a nipple 15 of a suitable air supply hose 16. An air discharge passage 17 is formed in the handle portion parallel to the passage 14.

The discharge passage 17 is closed at one extremity by means of a threaded plug 18. A valve cage 19 is threaded into the handle portion 11 so as to extend across the passage 17 and into communication with the passage 14. The head

2

of the cage 19 is closed by means of a tappet valve 21 which seats against a sealing gasket 20.

The valve 21 is provided with a stem 22 extending throughout the length of the cage 19 and projecting forwardly therefrom. The cage 19 is provided with air ports 23 which align with the passage 17 so that when the valve 21 is forced away from the head of the cage 19, it will allow air to flow from the intake passage 14 to the discharge passage 17.

The valve 21 is constantly urged toward its seated position by means of a suitable compression spring 24. A trigger member 25 is positioned in a trigger channel 26 in the handle portion 11. The trigger member 25 is mounted on a hinge pin 27 so that it may be pulled rearwardly by the fingers of the user to actuate the valve 21 to cause air to discharge from the bushing 13.

The nut 12 is designed to receive any desired spray mechanism. As illustrated, the nut is threaded onto a male nipple 28 of a T-fitting 29. The T-fitting 29 is provided with a second male nipple 30 projecting oppositely outward from the nipple 28 in axial alignment with the latter, and with a third male nipple 31 projecting downwardly at right angles to the first two nipples.

A jet nozzle 32 is threaded into the bushing 13. The nozzle 32 is provided with a stop flange 33 which is clamped between the bushing 13 and the bottom of the nipple 28 to accurately locate the jet nozzle in place therein. The jet nozzle 32 extends through a guide opening 34 in the T-fitting 29 and into an axial bore 35 therein.

The bore 35 is designed to receive the extremity of a spray nozzle tube 36. The nozzle tube 36 is provided with a locking flange 37 thereon which is clamped against the extremity of the nipple 30 by means of a clamp nut 38, threaded on the second male nipple 30, so as to properly position the tube 36 in the T-fitting 29. The inner extremity of the tube 36 is slotted, as shown at 39, so that it may extend past an orifice nozzle 40.

The orifice nozzle 40 extends into the extremity of a suction tube 41 and the latter is threaded into the nipple 31 of the T-fitting 29. The orifice nozzle is provided with an accurately positioned seating flange 42 which is clamped against a seat in the bottom of the nipple 31 by means of the tube 41 to accurately position the upper extremity of the nozzle at the best operating position within the spray tube 36.

A container cap 43 is threaded onto the third nipple 31 and is adapted to receive a container 44 for the material to be sprayed. The upper

3

extremity of the container 44 extends within a sleeve 45 projecting downwardly from the cap 43, and is locked in place in the sleeve 45 by means of locking pins 46 carried by the container, which engage in bayonet slots 47 in the sleeve 45.

The top of the container is sealed by means of a sealing plate 48 which is mounted on guide pins 49 in the cap 43, and which is constantly urged downwardly against the top of the container 44 by means of compression springs 50. A sealing gasket 51 is secured to the plate 48 to seal the latter to the upper edge of the container 44. A resilient sealing ring 52 is mounted in the plate so as to snugly enclose the suction tube 41.

It can be readily seen that air discharging from the jet nozzle 32 over the orifice nozzle 40 will create a partial vacuum in the suction tube 41 to elevate material to be sprayed or blasted from the container 44.

The spray nozzles 36 wear away rapidly, when used for abrading or sand blasting purposes. They can be easily replaced by simply loosening the nut 38 and slipping a new one into position without disturbing the remainder of the device. This is also true of the orifice nozzle 40, which can be removed by simply unscrewing the suction tube 41 so that a new one may be threaded therein and replaced.

Occasionally, through long or careless use, the material will abrade completely through the tube 36 into the T-fitting 29. In the usual sprayer or blast gun this requires the entire gun to be discarded. In this improved sprayer, however, it is only necessary to discard the T-fitting 29 and replace it with a new one.

While a specific form of the improvement has been described and illustrated herein, it is to be understood that the same may be varied, within the scope of the appended claims, without departing from the spirit of the invention.

Having thus described the invention, what is claimed and desired secured by Letters Patent is:

1. A construction for abrasive guns and fluid sprayers comprising: a T-fitting; two oppositely projecting and axially aligned threaded nipples formed on said T-fitting; a third threaded nipple projecting downwardly at right angles to the axis of the first nipples; a container mounted on the third nipple; a spray nozzle mounted on one of the first nipples; a valved air supply member mounted on the other of the first nipples; a suction tube extending downwardly from within the third nipple into said container; and an air jet member clamped between said air supply member and said T-fitting for projecting a jet of air into said spray nozzle.

2. A construction for abrasive guns and fluid sprayers comprising: a T-fitting; two oppositely projecting and axially aligned threaded nipples formed on said T-fitting; a third threaded nipple projecting downwardly at right angles to the axis of the first nipples; a container mounted on the third nipple; a spray nozzle mounted on one

of the first nipples; a valved air supply member mounted on the other of the first nipples; a suction tube extending downwardly from within the third nipple into said container; an air jet member clamped between said air supply member and said T-fitting for projecting a jet of air into said spray nozzle; and an orifice nozzle mounted in the extremity of said suction tube and projecting upwardly within said spray nozzle.

3. A construction for abrasive guns and fluid sprayers comprising: a T-fitting; two oppositely projecting and axially aligned threaded nipples formed on said T-fitting; a third threaded nipple projecting downwardly at right angles to the axis of the first nipples; a container mounted on the third nipple; a spray nozzle mounted on one of the first nipples; a valved air supply member mounted on the other of the first nipples; a suction tube extending downwardly from within the third nipple into said container; an air jet member clamped between said air supply member and said T-fitting for projecting a jet of air into said spray nozzle; an orifice nozzle mounted in the extremity of said suction tube and projecting upwardly within said spray nozzle; a cap member threaded on said third nipple and acting to cover and support said container in said cap member; a sealing plate within said cap member; and means acting between said cap member and said plate to force the latter into sealing contact with said container.

4. Means for mounting a container on an abrasive gun comprising: a threaded nipple projecting downwardly from said gun; a flanged cap member threaded on said nipple, said container extending upwardly within said cap member; pins projecting from said container into bayonet slots in said cap member; a sealing plate resting on said container within said cap member; guide pins supporting said sealing plate from said member; and springs urging said plate downwardly against said container.
